ORIFICE RING USED IN GLASS FORMING
MACHINERY AND THE LIKE

A. Daniel Fentzke, Wethersfield, Conn., assignor to
Emhart Industries, Inc.

Filed June 25, 1975, Ser. No. 590,233

Term of patent 14 years

Int. Cl. D15—09

U.S. Cl. D55—1 H

Fig. 4

Fig. 5

Fig. 6

Fig. 7

FIG. 1 is a top view of an orifice ring used in glass forming machinery and the like embodying my new design.

FIG. 2 is a front elevation view thereof, the rear elevation being identical thereto.

FIG. 3 is a side elevation view thereof, the opposite side being identical thereto.

FIG. 4 is a bottom view thereof.

FIG. 5 is a cross-section view thereof taken along line 5-5 of FIG. 1.

FIG. 6 is a cross-section view thereof taken along line 6-6 of FIG. 1.

FIG. 7 is a cross-section view thereof taken along line 7-7 of FIG. 1.

I claim:

The ornamental design for an orifice ring used in glass forming machinery and the like, as shown and described.
